(57) **CLAIM**

The ornamental design for a light fixture, as shown and described.

DESCRIPTION

In a preferred embodiment, the nature of this product is a light fixture in the form of a lighted wall sconce with or without a mirror backing.

FIG. 1 is a top, front and left side perspective view of a light fixture, showing our new design;

FIG. 2 is a front elevational view thereof;

FIG. 3 is a left side elevational view thereof, the right side elevational view being a mirror image; and,

FIG. 4 is a top plan view thereof, the bottom plan view being a mirror image.

The broken line representations of fasteners in the figures and of a mirror backing in FIGS. 1-4 are for the purpose of illustration only, and form no part of the claimed design.
